UNITED STATES PATENT OFFICE.

FREDERICK G. KEYES, OF EAST ORANGE, NEW JERSEY, ASSIGNOR TO COOPER HEWITT
ELECTRIC COMPANY, OF HOBOKEN, NEW JERSEY, A CORPORATION OF NEW JERSEY.

VAPOR ELECTRIC APPARATUS.

1,235,699.

Specification of Letters Patent.

Patented Aug. 7, 1917.

Application filed November 24, 1913. Serial No. 802,753.

To all whom it may concern:

Be it known that I, FREDERICK G. KEYES, a citizen of the United States, and resident of East Orange, county of Essex, State of New Jersey, have invented certain new and useful Improvements in Vapor Electric Apparatus, of which the following is a specification.

The present commercial quartz lamp is usually supplied with two liquid electrodes and the lamp is operated in a manner suited to the presence of a liquid anode and a liquid cathode. It has been proposed to substitute for the liquid anode an anode of tungsten or some other material capable of resisting the high temperatures to which the elements of the lamp are liable to be subjected.

It is well known that quartz lamps, when first lighted, permit a large current to flow. It is also known that lamps of this type operate at a high pressure. If the initial current mentioned above is confined to the anode without the presence of any conducting substance of suitable capacity connected therewith, a heavy spattering will be caused and the rise of pressure will be retarded. I overcome these difficulties by using a tungsten anode and causing the shank of the said anode to pass through a mass or puddle of mercury or other liquid conducting material from which the shank or stem of the anode emerges so as to cause the anode proper to be exposed within the lamp to the immediate effects of the operation thereof, being prevented, however, by a throttle or barrier usually in the form of a ring from projecting into the luminous tube any spattering which may be caused.

Incidentally I have contributed to the surmounting of one of the chief obstacles to the utilization of tungsten anodes, by winding fine tungsten wire into a flat spiral which forms the exposed part of the anode. In this way the difficulty now existing of obtaining suitable tungsten foil is obviated. Besides, it is found that this form of anode results in cheapness of construction, and a comparatively even distribution of temperature, while making it unnecessary to rivet the stem or shank to the anode proper.

In the drawings, Figure 1 is a side eleva-

tion of the lamp constructed in accordance with my invention. Fig. 2 is a plan and Fig. 3 is a detail view of the tungsten anode.

Referring to the drawings in detail, 1 represents the luminous tube of a lamp made of quartz or highly refractory glass. The cathode, surmounted by a condensing chamber, 3, is shown at 2, while the anode appears at 4 in the form of a spiral, as shown in detail in Fig. 3. The shank or stem 5 of the spiral is, of course, in one piece with the spiral, so that no riveting is required. In passing out of the lamp at a seal, 9, the shank traverses a chamber, 6, surmounted by a condensing chamber, 7, the chamber, 6, being substantially filled with mercury or other good conducting liquid. Between the anode, 4, and the main body of the luminous tube, 1, I construct a ring, 8, either closely fitting within the tube, 1, or integral therewith. The object of this ring is to constitute a throttle or barrier for preventing any spattering of the anode which may occur from being carried into the luminous portion of the tube. In the present state of the art it does not seem necessary to illustrate the action of the auxiliary apparatus which is usually employed for tilting mercury vapor lamps, whether of quartz or of glass in order to start the operation. It may be said, however, that in the non-operating position of the lamp, the cathode end is considerably below the normal operating plane. When, however, the circuit is completed, the auxiliary mechanism lifts the cathode end and causes the mercury to flow into the anode chamber, 6, incidentally causing a rupture of the circuit which inaugurates the current flow through the tube.

The tungsten anode, 4, is quickly raised to a white heat, and a considerable portion of this heat is transferred to the mercury immediately surrounding the shank, 5, whereby a rapid rise in pressure is brought about, while the anode itself is kept comparatively cool.

Moreover the shifting of the position of the anode chamber, 7, during the normal operation of the device,—namely the position shown in Fig. 1 of the drawings—tends to retard any spattering which might occur under the usual operating conditions. All excessive heat is thus prevented from

reaching the seal 9 at the lower end of the shank, and thus both the seal 9 and the cathode seal, 10, are kept at approximately the same temperature. By my invention the 5 heavy initial spattering at the instant of tilting is retarded; the spattering during normal operation is reduced, the heat being spent in evaporating the mercury; the access of heat to the seal at the shank of the anode, 4, is prevented, thus keeping it at approximately the same temperature as the negative seal.

Otherwise expressed, the total energy 15 passing through the lamp being carried by the anode, 4, the anode reaches a very high temperature which is conducted down the stem to the mercury. This energy is expended in evaporating the mercury which brings about a rise in pressure until equilibrium is finally established. In making 20 this statement it is assumed that the chambers, 3 and 6, are provided with suitable radiating surfaces for maintaining them at the proper level.

25 In speaking of the normal operating position of the tube, the cathode end is assumed to be about five degrees higher than the anode end reckoned from the horizontal plane.

30 The depression shown in full lines at 11 in Fig. 1 and in dotted lines in Fig. 2 is a trough in which a portion of the liquid cathode lies exposed at the mouth of the luminous tube 1.

35 In employing the term "metal" in the attached claim, reference is had not necessarily to the pure metal, as an alloy may be employed if found suitable. Similarly, the term "quartz lamps or the like" is intended

to include lamps constructed of a highly 40 heat resisting glass.

Summing up once more the various functions of the apparatus herein described, it may be stated that in the usual operation of such apparatus the seal gets very hot 45 owing to the high temperature developed in the solid anode.

One function of the lamp is to prevent this excessive heating and another function of it is to make it easier to obtain a high 50 pressure within the lamp. This high pressure is brought about by the heat that is developed on the anode being transmitted along the stem and communicated to the mercury, causing a volatilization of the mercury. Thus a third function of the apparatus is to provide means whereby the heat of the tungsten anode passes down into and is absorbed by the mercury. The heat, being spent in evaporating mercury, prevents excessive spattering because it cannot maintain such a high temperature.

I claim as my invention:

In a quartz lamp, a luminous tube, a liquid cathode exposed at one end of said tube, a solid anode at the opposite end consisting of a flat spiral of tungsten, in combination with a barrier between the spiral and the main body of the luminous tube, such barrier consisting of an internal ring within 65 the end of the said tube.

Signed at New York in the county of New York and State of New York this 21st day of November A. D. 1913.

FREDERICK G. KEYES.
